DESIGN FOR A GILET

Jacob J. Kadet, Chicago, Ill., assignor to Kadet
Kruger & Company, a corporation of Illinois

Application September 16, 1940, Serial No. 95,090

Term of patent 3½ years

To all whom it may concern:

Be it known that I, Jacob J. Kadet, a citizen of the United States, residing at the city of Chicago, county of Cook, and State of Illinois, whose post-office address is % Kadet Kruger & Company, 216 West Adams Street, Chicago, Illinois, have invented a new, original, and ornamental Design for a Gilet, of which the following is a specification, reference being had to the accompanying drawing, forming a part thereof.

Fig. 1 is a front perspective view of a gilet showing my new design; and

Fig. 2 is a rear view of the same, slightly reduced in size.

I claim:

The ornamental design for a gilet, as shown.

JACOB J. KADET.
